(57) **CLAIM**

The ornamental design for a “display base,” as shown and described.

DESCRIPTION

FIG. 1 is a perspective view of display base showing our new design;

FIG. 2 is a front view thereof;

FIG. 3 is a rear view thereof;

FIG. 4 is a left side elevational view thereof;

FIG. 5 is a right side elevational view thereof;

FIG. 6 is a top view thereof;

FIG. 7 is a bottom view thereof;

FIG. 8 is a perspective view showing the usage state of the display base; and,

FIG. 9 is a side elevational view showing the usage state of the display base.

The broken line showing of a display in FIGS. 8 & 9 is included for the purpose of illustrating environment, and forms no part of the claimed design.
